CANE MILL

Ernst W. Kopke, Baton Rouge, La.

Application August 13, 1935, Serial No. 36,014
Renewed June 17, 1939

9 Claims. (Cl. 100—47)

This invention relates to mills for extracting sugar from sugar cane and more particularly to the type of mill which has three rolls. One object of my invention is to produce a sugar cane mill construction which will be more efficient than the mills heretofore known and which can be embodied in mills of the prior art without rebuilding the entire mill. A characteristic of this invention is that the feed roll and turn plate 10 are free-floating.

In the ordinary three-roll sugar cane mill the top roll is provided with hydraulic rams which bear on the brasses or bearings at the end of the roll in such manner as to press the top roll in a downward direction. The pressure for these hydraulic rams is provided by means of an accumulator. By means of this hydraulic ram arrangement the top roll can yield when an excessive amount of sugar cane passes between the feed 20 roll and the top roll. Inasmuch as the opening between the feed roll and the top roll is greater than between the top roll and the discharge roll it follows that any variation in position of the top roll due to the entrance of an abnormal 25 amount of cane between the top roll and the feed roll will cause a greater variation of the pressure between the discharge roll and the top roll. Owing to the difference in pressure at the two points where the cane is squeezed in a three- 30 roll mill the operation of the machine is very inefficient. If the force exerted by the rams is resolved into components it will be found that the greater pressure existing between the discharge roll and the top roll produces an un- 35 balanced condition in which there is a component force tending to obstruct free movement of the top roll. Furthermore, the fact that only certain components of the force of the hydraulic ram can be effective in squeezing the cane it follows that excessively powerful driving means are 40 required. Furthermore, in mills heretofore known the turn plate has been fixedly mounted so that it cannot adjust itself to operate properly on different thicknesses of cane passing over it. 45 Due to the fixed position of the discharge roll and the restricted action of the top roll due to the frictional trouble above-mentioned it follows that where maceration of the cane is practised the results vary widely from minute to minute. 50 Without uniformity it is of course impossible to adjust the machine to maximum efficiency.

In a three-roll mill made in accordance with this invention there are provided hydraulic rams which press the feed roll towards the top roll. 55 The feed roll is mounted by means of a three-

point suspension, that is to say, with two rams, one at each end of the roll beneath the journal boxes and arms extending from the journal boxes to a point midway between the ends of the roll and at one side of the roll, i. e., the discharge 10 side of the machine, where the levers join and are pivotally connected to a fixed member by a universal joint. This makes it possible for the feed roll to move vertically as a whole or to tilt through a small arc.

In order that this construction may cooperate properly with the other parts of the machine the usual turner bar and plate are mounted on the arm or arms carrying the feed roll. By mounting the turner plate in this way it is adjusted from moment to moment automatically by the machine in accordance with the amount of cane entering between the feed roll and the top roll. Mounting the turn beam and turn plate on the means supporting the feed roll permits of obtaining an accurate control of the pressure between the top roll and feed roll as well as between the discharge roll and the top roll to produce a uniform crushing. It also makes possible obtaining a high percentage extraction by introducing water or the mixed juices at the turn plate and has other advantages, not the least of which is the elimination of the necessity for surplus power to take care of momentary high pressures between the rolls. The mounting of 20 the feed roll as described and the application of the power used in a direction which permits of the rolls moving readily produce a compact machine which operates in a very efficient manner.

Referring now to the drawings—

Fig. 1 is a view in elevation of a mill constructed in accordance with this invention, a side portion of the frame being removed and parts broken away in order to show other parts more clearly;

Fig. 2 is a horizontal sectional view taken as on line 2—2 of Fig. 1;

Fig. 3 is a longitudinal vertical section taken through a side portion of the frame as on line 3—3 of Fig. 2; and

Fig. 4 is a partial transverse vertical section taken as on line 4—4 of Fig. 2 and showing only parts shown in Fig. 2.

As shown in the drawings, a cane mill constructed in accordance with this invention is 50 provided with a frame comprising side portions 1 and 2 joined by a cross or tie member 3. The frame may be mounted upon a suitable base or foundation, not shown. The side portions are shown as cast members of substantially trian-

5 gular shape and having spaced side walls 1^a, 1^b and 2^a, 2^b respectively, joined by suitable trans-
10 verse partitions 1^c and 2^c arranged to provide a number of chambers in each side portion, and
15 at some of the chambers, portions of the side walls are omitted to provide access thereto. In chambers near the bottoms at one end of the side portions 1 and 2 of the frame are mounted jacks or rams 4 supplied with pressure from suitable
20 compressed air or hydraulic pressure systems, not shown. The plungers 5 of the jacks or rams 4 support journal boxes 6 slidably mounted in the side portions of the frame 1, suitable bearing blocks 8 and 10 being interposed between the
25 plungers 5 and the journal boxes 6 and between the jacks 4 and the frame, respectively. Journalled in the boxes 6 are the journals 12 of a discharge roll 14 which cooperates with a top roll 16 having journals 18 mounted in bearings
30 20 at the upper portion of the side portions 1 and 2 of the frame. Suitable cap pieces 22 secure the journals 18 in position in the frame. Channel members 23 and 24 are bolted to the ends of the side portions of the frame to re-enforce the
35 frame against the stresses resulting from the action of the jacks upon the rolls.

In other recesses formed at the opposite ends of each side portion of the frame rams or jacks 26 are mounted. These jacks are also supplied with
40 fluid under pressure from the system which supplies the jacks 4 and have suitably curved bearing plates 27 between the jacks and the frame. The plunger 29 of each jack 26 supports an end 30 of a yoke 32, suitable bearing plates 31 being
45 interposed therebetween. On each end 30 there is mounted a journal box 33 which receives a journal 34 of the feed roll 36. The yoke 32, as shown in Figure 2, is of substantially U-shape with the ends 30 lying between the side plates 1^a and 1^b, 2^a and 2^b of the side portions 1 and 2 respectively of the frame and joined by a trans-
50 verse portion 37 of substantially T-cross-section, which extends through openings in the inner side plates 1^b and 2^b. Projecting from the trans-
55 verse portion 37 in the direction opposite to the ends 30 are the converging arms 38^a, 38^b and 38^c which are formed integral with the transverse portion 37 and are united to form a bearing housing 38^d shaped to receive a substantially spherical bearing portion 39 formed on a shaft 40 which is provided with journal portions mounted in housings 41^a and 41^b carried by the transverse member 3.

Adjacent the opposite ends of the transverse portion 37 of the yoke, bolts, not shown, secure bearing blocks 43 to the upper face of the trans-
60 verse portion 37, the blocks 43 being adjusted to the desired position by the set screws 45 mounted in lugs 47 formed integral with the transverse portion 37. The bearing blocks 43 are provided with openings in which are journalled trunnions 46 at the ends of a turner bar 48 which has secured to its upper end the usual turner plate 50. Pivotaly mounted on the arm 38^b of the yoke is a
65 lever 52 the upper end of which bears against the turner bar 48 while the lower end of the lever is pivotally connected to one end of a link 54, the other end of which passes through a lug 55 formed integral with the member 38^b and is
70 threaded to receive a nut 56 so that adjusting the nut 56 will cause the lever 52 to bear against the turner bar 48 and hold the turner plate 50 in contact with the roll 36.

In the arrangement shown the cane is fed
75 between the feed roll 36 and the top roll 16, suit-

able pressure being supplied to the jacks 26 so as to cause the cane to be crushed between the rolls 36 and 16 and the juice extracted therefrom. Stops 58 are provided to engage with the ends 30 of the yoke and limit the movement of the roll 5 36 towards the roll 16. Adjustment of the minimum distance between the rolls may be made by means of suitable shims 59 carried by the ends 30. The crushed cane passes from the roll 36 across the turner plate 50 and between the discharge roll 14 and the top roll 16, suitable pressure being supplied to the jacks 4 to accomplish the desired degree of extraction from the cane. Stops 60 are provided to limit the movement of the roll 14 towards the roll 16 and adjustment of the minimum distance between the rolls is made by means of suitable shims 61.

The volume of cane fed to the feed roll 36 usually is not uniform nor is the cane uniformly distributed across the surface of the roll 36. When more cane is fed at one end of the roll than the other the jack 26 at that end of the roll yields under the increased pressure permitting the roll to tip slightly with respect to the roll 16. The connection of the yoke 32 with the transverse member 3 permits of the tilting movement of the roll 36 or of a movement of the roll 36 in an arc toward and away from the roll 16. The movement of the roll 36 with respect to the roll 16 does not affect the pressure applied thereto nor does it in any way affect the pressure to which the cane is subjected between the rolls 14 and 16 and vice versa. The turner plate 50 being mounted on the yoke 32 is fixed in its relation with respect to the roll 36 so that the turner plate is moved from the roll 16 as the roll 36 is moved therefrom, thus providing suitable space between the roll 16 and the turner plate 50 for the passage of a volume of cane which causes a movement of the roll 36 from the roll 16. This relation of the turner plate 50 with respect to rolls 36 and 16 permits of supplying the cane in its passage over the turner plate 50 with a suitable quantity of water or mixed juices so as to provide for proper maceration of the cane during its passage between the rolls 14 and 16.

What is claimed is:

1. In a cane mill, a frame, a top roll having a fixed axis in said frame, a feed roll cooperating with said top roll, a yoke in which said feed roll 50 is mounted for movement with respect to said top roll, said yoke having a universal connection to said frame and means to apply pressure to said feed roll.

2. In a cane mill a frame, a cane crushing roll, 55 a yoke in which said roll is mounted and means connecting said yoke and frame providing a universal connection.

3. In a cane mill, a frame, a cane crushing roll, 60 a yoke having bearings in which said roll is journaled, means providing a universal connection between said yoke and frame in the central plane of the frame and means yieldingly supporting said yoke at said bearings. 65

4. In a cane mill, a frame, a cane crushing roll, 70 a yoke in which said roll is mounted, means providing a universal connection between said yoke and frame at a single point in the central plane of the frame and a turner plate mounted on said yoke for cooperation with said roll.

5. In a cane mill, a frame, a cane crushing roll, 75 a yoke in which said roll is mounted, means providing a universal connection between said yoke and frame, means yieldingly supporting said yoke 80

- at the roll and a turner plate mounted on said yoke for movement with said roll.
6. In a cane mill, a frame, a cane crushing roll, a yoke in which said roll is journalled, means providing a universal connection between said yoke and frame, means for applying pressure to said roll, a turner plate mounted on said yoke for cooperation with said roll and means for engaging said plate with said roll.
- 10 7. In a cane mill, a frame, a cane crushing roll, a yoke in which said roll is journalled, means on the central axis of said yoke providing a universal connection between said yoke and said frame, yielding means for applying pressure to said roll
- 15 at the ends thereof, a turner plate carried by said yoke and means for engaging said plate with said roll.
8. In a cane mill, a frame, a cane crushing roll, bearings in which said roll is journalled, roll holding means in which said bearings are mounted, 5 said roll holding means having a universal connection with said frame, and means for applying pressure to said roll.
9. In a cane mill, a frame having a transverse member, a cane crushing roll, roll holding means 10 having a universal connection with said transverse member at the center thereof and means for applying pressure to said roll engaging said roll holding means.
